JOURNAL-BOX LUBRICATION

John F. Corcoran, Winnetka, and Robert E. Cryor, Hinsdale, Ill., and Clinton Rector, Alexandria, Va., said Corcoran and said Cryor, assignors to Union Asbestos & Rubber Company, Chicago, Ill., a corporation of Illinois

Application May 13, 1953, Serial No. 354,776

7 Claims. (Cl. 308—88)

This invention relates to improvements in railway car journal bearings, and more particularly to the use of particular materials as lubricant applicators in railway car journal bearings, whereby the use of such particular materials brings about new, improved, unexpected and beneficial results.

One of the most serious problems of railroads is the "hot-box." Despite many, many years of research and attempts to improve railway car journal bearings, these journal bearings still get hot and bring about breakdowns in equipment.

One of the principal causes of the "hot-box" is the use of conventional cotton waste as the material for applying lubricant to the railway car journal bearing. In the usual railway car journal bearings, the stuffing box in which the bearing is located has a mass of cotton waste located in the bottom portion thereof, which mass of waste is soaked with lubricant. As the journal turns, lubricant is applied to the journal from the cotton waste. Unfortunately, as the journal rotates, sometimes some of the cotton waste is picked up by the journal and is carried between the journal and the journal bearing, or brass as it is sometimes referred to. Once the cotton waste gets between the journal and the journal brass, it is burned, carbonized, or coked by the high temperature caused by friction between the journal and the bearing.

The carbonizing or coking of the cotton waste results in a gritty substance, and this gritty substance acts as an abrasive which scores the journal. A scored journal is more apt to "grab" or pick up cotton waste and drag it between the journal and the journal brass, and, thus, once the journal is scored the tendency to get a "hot-box" is greatly increased.

Many devices have been tried, without success, to prevent "waste grabs" by the journal, that is, the action by the journal in dragging cotton waste up between the journal and the journal brass. However, none of these devices have been fully effective and as long as cotton waste is used for feeding or applying oil to the journal, some of the cotton waste will be dragged up between the journal and the journal brass.

Most of the devices tried, to date, to prevent "waste grabs" by the journal comprise retainers for holding the cotton waste tightly against the underside of the journal and for preventing the cotton waste from creeping up between the journal and the journal brass. The lack of success of these retainers is due, in large part, to the fact that a slightly scored journal picks up cotton waste and drags the cotton waste past the retainer into the journal brass.

Thus, one of the objects of this invention is to provide means for eliminating the above referred to causes of "hot-boxes" in railway car journal bearings.

Another object of this invention is to provide a lubricated journal for railway cars wherein the possibility of "hot-boxes" by reason of carbonizing or coking of the lubricant applicator is eliminated, and whereby waste retainers may be eliminated from the journal-box.

2

A further object of this invention is to provide particular materials for use as lubricant applicators to railway car journal bearings, the use of such materials being effective to eliminate carbonizing or coking of the lubricant applicator and to eliminate the scoring of the journal due to carbonizing or coking of lubricant applicator, which, at present results when conventional cotton waste is used as the lubricant applicator.

Further objects and advantages of this invention will become apparent as the following description proceeds and the features of novelty which characterize this invention will be pointed out with particularity in the claims annexed to and forming part of this specification.

In its broadest concept, the objects of this invention are attained by substituting, for the body of cotton waste conventionally used in journal-boxes, a body of thermoplastic, flame-resistant, resinous fibers having capillarity of a range comparable with that of cotton waste to insure absorption of lubricant from the lubricant reservoir and feeding of the lubricant to the journal, and which thermoplastic, resinous fiber has the property of melting to a liquid state at the elevated range of temperatures attained by the journal brass.

With the use of such a thermoplastic, flame-resistant, resinous fiber, as the lubricant applicator, if some of the material is carried by the journal into the journal brass, the elevated temperatures in the journal brass cause the material to melt to a liquid state and run out of the journal brass and off the journal back to the body of fibers serving as the lubricant applicator. Since the material does not carbonize or coke there is no formation of gritty carbonized end products and, consequently, scoring of the journal is avoided. The approximate temperature range within which the material should melt is 225°—400° F.

A preferred embodiment of the invention is shown in the accompanying drawing, in which:

Figure 1 is a fragmentary side view of a railway car journal box with the hinged cover of the box broken away to show the position of the journal and its bearing member; and

Figure 2 is a vertical section taken on line 2—2 of Figure 1.

Referring now to the figures, the journal bearing structure comprises an axle journal 10, a journal bearing 12, and a bearing wedge 14. The bearing wedge 14 is interposed between the bearing member 12 and the top portion of a journal box 16. The journal box 16 is normally closed by a hinged lid 18, but this element is broken away in Figure 1 of the drawing to show the arrangement of the journal 10, the journal bearing 12, and the wedge member 14. The journal bearing 12 may be of the usual construction and includes a brass casting provided with a lining 20 of lead or other suitable bearing material, which lining 20 seats on the journal 10 between the collar 12 at one end and the fillet 24 at the other end of the journal.

The opposite sides of the journal bearing 12 engage vertical guide ribs 26—26 formed on the opposed inner side faces of the journal box 16. Lugs 28—28 on said bearing 12 engage the forward faces of the guide ribs 26—26 to hold the bearing in position. The inner end of the wedge 14 engages an upstanding collar portion 30 formed on the bearing 12, and the other end of the wedge 14 is positioned back of a lug 32 located near the open side of the journal box 16.

Lubricant is applied to journal 10 and to the bearing 12 by means of a body of lubricant saturated material 34 which is located in the bottom portion of the journal box 16 so as to press resiliently at the bottom and side portions of the journal 10.

A portion of lubricant saturated material 34 may be

formed into a roll 36, if desired, and may be applied so as to engage the inner fillet portion 24 of the journal 10. A main portion of the body of material 34 may be positioned beneath the journal so as to extend upwardly at the sides of the journal to a position near, but preferably slightly below the center of the journal 10. A portion of the body of material 34 may be formed as a wedge 38 positioned in the forward portion of the box 16 to prevent cinders or grit from finding entrance to the main body of the lubricant applying material 34.

The body of lubricant applying material 34 is formed of thermoplastic, flame-resistant, resinous fibers as above set forth and as more thoroughly described as follows.

The absorbent materials suitable for use in the novel journal bearing structure of this invention are thermoplastic resinous fibers having a melting point within the range of 225° to 400° F. These fibers unlike cotton, rayon, wool or silk, are characterized by their ability to soften and melt upon subjection to heat without the formation of gritty carbon or coke which, as pointed out above, so seriously fouls the bearings. The resins from which these fibers are made are capable of resisting decomposition and of retaining their original chemical composition after melting within the temperature range of 225° to 400° F.

The thermoplastic fibers are preferably bibulous multifilamentary staple fibers or yarns, since the physical structure of such fibers renders them better capable of absorbing the liquid lubricant, e. g. mineral oils, used in the journal box. For this reason the monofilamentary fibers sometimes produced from these thermoplastic resins are not as well suited, although a mass of such fibers, wettable by the liquid lubricant, may be useful. Preferably, however, the fibers are both wettable by the lubricant and possess a bibulous multifilamentary structure.

It is anticipated that fibers prepared from the following thermoplastic organic resins can be employed in the practice of this invention; polyamides, polyacrylonitrile, cellulose acetate, copolymers of acrylonitrile and vinyl chloride, copolymers of vinyl chloride and vinyl acetate, copolymers of vinylidene chloride and vinyl chloride, polyesters and polyvinylchloride. Other fiber-forming resins having the above enumerated physical and chemical properties will be apparent to those skilled in the art.

While there has been shown and described a particular embodiment of this invention, it will be obvious to those skilled in the art that various changes and modifications may be made therein without departing from the invention and, therefore, it is intended in the appended claims to cover all such changes and modifications as fall within the true spirit and scope of the invention.

What we claim as new, and desire to secure by Letters Patent of the United States, is:

1. In combination, a railway car journal bearing structure, and means including a body of absorbent material normally impregnated with a liquid lubricant and positioned to apply said lubricant to said structure, said absorbent material comprising thermoplastic resinous fibers having a melting point within the range of 225° to 400° F.

2. In combination, a railway car journal bearing structure, and means including a body of absorbent material normally impregnated with a liquid lubricant and positioned to apply said lubricant to said structure, said absorbent material comprising bibulous thermoplastic resinous fibers wettable by the lubricant and having a melting point within the range of 225° to 400° F.

3. In combination, a railway car journal bearing structure, and means including a body of absorbent material normally impregnated with a liquid lubricant and positioned to apply said lubricant to said structure, said absorbent material comprising bibulous thermoplastic resinous fibers having a melting point within the range of 225° to 400° F., said fibers being wettable by the lubricant and capable of retaining substantially the original chemical composition thereof after melting within said temperature range.

4. In combination, a railway car journal bearing structure, and means including a body of absorbent material normally impregnated with a liquid lubricant and positioned to apply said lubricant to said structure, said absorbent material comprising multifilamentary organic thermoplastic resinous fibers having a melting point within the range of 225° to 400° F., said fibers being wettable by the lubricant and capable of retaining substantially the original chemical composition thereof after melting within said temperature range.

5. In a railroad car journal bearing structure which includes a railroad car journal bearing and means including a body of absorbent material normally impregnated with a liquid lubricant and positioned to apply said liquid lubricant to the journal bearing, the improvement wherein said absorbent material comprises thermoplastic resinous fibers having a melting point within the range of 225° to 400° F.

6. In a railroad car journal bearing structure which includes a railroad car journal bearing and means including a body of absorbent material normally impregnated with a liquid lubricant and positioned to apply said liquid lubricant to the journal bearing, the improvement wherein said absorbent material comprises bibulous thermoplastic resinous fibers wettable by the lubricant and having a melting point within the range of 225° to 400° F.

7. In a railroad car journal bearing structure which includes a railroad car journal bearing and means including a body of absorbent material normally impregnated with a liquid lubricant and positioned to apply said liquid lubricant to the journal bearing, the improvement wherein said absorbent material comprises multifilamentary organic thermoplastic resinous fibers having a melting point within the range of 225° to 400° F.
